COMBINED BOTTLE AND CLOSURE CAP

Bernard Strong, Middlesex, England

Application October 10, 1955, Serial No. 38,318

Claims priority, application Great Britain October 4, 1955

Term of patent 14 years

(Cl. D58—26)

FIG. 1.

FIG. 2.

FIG. 3.

FIG. 4.

Fig. 1 is a side elevational view, Fig. 2 is a front elevational view, Fig. 3 is a plan view, and Fig. 4 is a side and bottom perspective view, of a combined bottle and cap showing my new design.

The dominant feature of my design resides in the portions shown in full lines.

I claim:

The ornamental design for a combined bottle and closure cap, as shown and described.
